UXEDO SHIRT

William Klein, New York, N. Y.

Application February 24, 1955, Serial No. 34,687

Term of patent 14 years

(Cl. D3—25)

FIG. 1

FIG. 2

Fig. 1 is a front elevational view of a tuxedo shirt, showing my new design;

Fig. 2 is an enlarged detail view of the area outlined by dot-and-dash lines in Fig. 1.

The bosom of the shirt is shirred and the rear of the shirt is of conventional appearance.

I claim:

The ornamental design for a tuxedo shirt, as shown and described.
